[57] CLAIM

The ornamental design for a chair, as shown and described.

DESCRIPTION

FIG. 1 is a front perspective view of a chair embodying our new design;

FIG. 2 is a side elevational view of our new design, the opposite side of which is substantially a mirror image thereof (with or without the handle shown in broken line);

FIG. 3 is a side elevational view of our new design wherein the push handles are shown in an alternate position and the seat back is separated from the body;

FIG. 4 is a front elevational view of our new design;

FIG. 5 is a rear elevational view of the design;

FIG. 6 is a top plan view of the design;

FIG. 7 is a front perspective view of our new design wherein one arm rest is removed;

FIG. 8 is a perspective view of our new design with both arm rests removed from the chair;

FIG. 9 is a side elevational view of our new design in an alternate position, the opposite side of which is substantially a mirror image thereof (with or without the handle shown in broken line);

FIG. 10 is a front perspective view of our new design in an alternate position;

FIG. 11 is a side elevational view of our new design in an alternate position, the opposite side of which is substantially a mirror image thereof (with or without the handle shown in broken line);

FIG. 12 is a side elevational view of our new design in an alternate position with both arm rests removed from the chair;

FIG. 13 is a front elevational view of our new design shown in FIG. 11;

FIG. 14 is a rear elevational view of the design shown in FIG. 11; and,

FIG. 15 is a top plan view of the design shown in FIG. 11;

The broken line showings of a handle, foot plates and foot plate mounting brackets are for environmental purposes only and form no part of the claimed design.
